TAG

George B. Ludy, Cedar Rapids, Iowa

Application December 2, 1931, Serial No. 578,472

2 Claims. (Cl. 40—21)

My invention relates to fastening devices and has particular relation to a tag adapted to be secured to any variety of article having an opening by which the tag may be secured.

5 I have observed that where a tag of the ordinary type which employs a string as a fastening device must be fastened in a small opening it is very difficult for the operator to poke the ends of the string through the opening. Furthermore the strings are likely to cut or saw 10 their way from the opening in the tag to the edge, so that the tag becomes lost. Furthermore the expense of tying a string to a tag represents a considerable part of the cost of the tag.

15 I have, therefore, devised a tag which may be made from a single sheet of material such as cardboard or the like, and in which a part of the tag itself is used as a fastening device. The portion of the tag which is used as a fastening device is flat and narrow and may therefore be inserted through slots or other narrow openings, where it was previously very difficult of insertion.

20 An object of my invention is to provide a one-piece tag having an integral fastening device which is flat and narrow so that it may be inserted in the device which is to be tagged.

25 Another object of my invention is to provide a tag of the above description, which may be secured in place in an extremely simple manner, but which when once fastened becomes locked in place so that it may not be readily removed.

30 Another object of my invention is to provide a device of the above character which is inexpensive to manufacture and simple and reliable in operation.

35 Other and further features and objects of the invention will be more apparent to those skilled in the art upon a consideration of the accompanying drawing and following specification wherein is disclosed a single exemplary embodiment of the invention, with the understanding, however, that such changes may be made therein as fall within the scope of the appended 40 claims without departing from the spirit of the invention.

In said drawing:

45 Figure 1 is a plan view of a tag made according to one embodiment of my invention.

Figure 2 is a plan view of a tag made according to another embodiment of my invention.

50 Figure 3 is a view in perspective of my device as it is fastened to an object such as a pocket

watch which has a relatively large opening to which the device may be fastened, and

5 Figure 4 is a view in perspective of my device as it is fastened to an object such as a wrist watch in which the tag must be fastened through a narrow slot in the object.

Referring now to the drawing for a more complete disclosure of this invention and particularly to Figure 2, there is indicated at 10 a tag which may be shaped in any desired form. The tag has a tongue portion 11 which is about as long as the tag itself, but which is narrower than the tag. The tongue is preferably cut at an angle or beveled at its outer end as indicated at 12. The very end of the tongue is preferably cut off to make a fairly blunt point as indicated at 13, and slots 14 are cut in the tongue, preferably on the side opposite the beveled portion 12. These slots slope inward and toward the point as shown, for a purpose hereinafter described. Material may be taken from the tongue in making the slots so that they have an appreciable width as shown at 14, or the slots may have enlarged openings 14b at their inner ends to enable the tongue to better engage the slot in the tag. The slots in the latter construction, are preferably made by cutting the material of the tongue so that the slots do not have any appreciable width as shown in Figure 1. Any combination of these indentations may be used, or any other suitable indentation.

hung on a hook or the like, for supporting the object which has been tagged.

Printed matter 21 may be placed on the tag in order that the device to which the tag is attached may be identified or the tag may be used to carry a printed advertising message.

The tag may be made of any suitable material such as paper, cardboard, or thin metal sheet, and may be used in different sizes and shapes. For instance, the greatest dimension of the tag may be transverse to the length of the tongue such as the tag shown in Figure 1. The tag may be cut in any manner to carry out the motif of the slots, that is, for instance, the ends of the tag may be cut at the same angle as the slot 16.

In the operation of tagging an object such as the watch 22, the tongue 11 is inserted through the ring 23 of the watch and the end 13 of the tongue inserted through the opening 17. As the tongue is pushed into the slot, the beveled side 12 forces the slotted edge of the tongue against the edge 18 of the slot, and any pull on the loop 24 formed by the tongue 11 results in causing the slot to slide over the edge 18 to fasten the tongue securely in place. The tag is previously marked with any name or identifying number to identify the watch or other object, and, if desired, the watch may be hung up on a hook or nail by means of the hole 19.

It is apparent that the tongue 11 may be readily inserted through any narrow opening in the object to be tagged, such as the narrow slot 24 between the strap 26 and the side of a wrist watch 27, where it would be extremely difficult to insert the string of the ordinary tag.

The tag may be cut complete with tongue and

slots in a single operation and, therefore, the tag is very inexpensive to make, and may be made by automatic machinery without any manual operations.

It is apparent that the wedging and fastening action secured may be obtained in other forms of the slots, and with other forms and types of tags. In fact my method of fastening may well be used in other structures, wherever a tongue is inserted in a slot, and for many other purposes. Such modifications of my invention may be made without departing from the spirit and scope of the invention as set forth in the appended claims.

Having thus described the invention, what is claimed as new and desired to be secured by Letters Patent is:

1. A tag comprising a main portion having a diagonal slot therein, and a tongue portion of a width less than the length of the slot, to be secured to the main portion, having an indentation on an edge thereof and beveled on the other edge, whereby, when the tongue is inserted in the main portion, the indented edge of the tongue is forced by the beveled edge into engagement with the edge of the diagonal slot in the main portion.

2. A tag comprising a body and a tongue extending therefrom, said tongue having indentations along one edge thereof extending inwardly and toward the free end of the tongue, said body having a closed slot therein adapted to receive said tongue, said slot extending in a direction toward both the free end of the tongue and the indented edge thereof.

GEO. B. LUDY.
